ATTORNEY

UNITED STATES PATENT OFFICE.

ELISHA T. WEYMOUTH, OF BROOKLYN, NEW YORK.

STEAM-RADIATOR.

SPECIFICATION forming part of Letters Patent No. 295,700, dated March 25, 1884.

Application filed August 4, 1883. (No model.)

To all whom it may concern:

Be it known that I, ELISHA T. WEYMOUTH, of Brooklyn, in the county of Kings and State of New York, have invented certain new and useful Improvements in Steam-Radiators, of which the following is a full, clear, and exact description, reference being had to the accompanying drawings, and to the letters of reference marked therein.

10 My invention relates especially to steam-radiators employed for heating purposes, and has for its object the production of a device cheap and simple to construct, and wherein provision is made for quickly expelling the air when steam is admitted, creating a rapid circulation.

20 My improved radiator consists, essentially, in a base-chamber provided with inlet and outlet valves in the usual manner, in combination with a number of vertical octagonal pipes of cast metal screwed into said base, each pipe containing a circulating-tube open at both extremities, and held in place by suitable cross-pieces engaging with the tube and the sides of 25 the radiating-pipe. The lower extremities of the circulating-tubes extend down into the base beneath the level of the steam-inlet.

30 In the drawings, Figure 1 is a view in elevation of my improved radiator, one of the pipes being shown in vertical section. Figs. 2 and 3 are views in elevation of a circulating-tube with its supporting-arms detached from the radiating-pipe. Fig. 4 is a cross-sectional view of the two tubes at line $x-x$ of Fig. 1.

35 Like letters of reference, wherever they occur, indicate corresponding parts in all the figures.

40 A is the base-chamber, formed of metal in the usual manner, provided with inlet-valve B, outlet C, and legs D.

E are the vertical radiating-pipes, made preferably octagonal in form, and screw-threaded at F for the purpose of engaging with base A.

G are the circulating-tubes, supported with- 45 in pipes E by means of arms H.

In placing the suspended tubes in position the supporting-arms may be cast into pipe E in the manner well known and understood by those skilled in the art.

50 The circulating-tubes, when held in place as indicated, are free to expand and contract without danger of fracture of any of the parts of the device.

55 In operation, when steam is admitted at B, the mouth of tube G being below the inlet, the steam will pass up pipe E, down the circulating-tube, and through the succeeding pipes and tubes in order, the circulation taking place immediately, being unretarded by the 60 air as is usually the case in radiators as heretofore constructed. It will thus be seen that my device is admirably adapted to the uses and purposes for which it is intended.

Having now fully described my invention, 65 what I claim as new therein, and desire to secure by Letters Patent, is—

1. In a steam-radiator of the character herein specified, the vertical octagonal radiating-pipes secured to a base-chamber, and having 70 circulating-tubes, open at both extremities, centrally supported by the two arms, substantially as shown and described.

2. In a radiator of the character herein specified, base-chamber A, having an inlet, B, and outlet C, octagonal radiating-pipes E, and circulating-tubes G, centrally supported in pipes B by means of the two arms H, the said tubes being open at both extremities, as set forth, and the whole combined and arranged to operate substantially as shown and described. 75 80

In testimony that I claim the foregoing I have hereunto set my hand in the presence of two witnesses.

ELISHA T. WEYMOUTH.
